WRAPPING MACHINE

Robert E. Taggart and James C. Travis, Anderson, Ind., assignors to Lynch Corporation, Anderson, Ind., a corporation of Indiana

Application December 13, 1954, Serial No. 474,898

12 Claims. (Cl. 53—225)

This invention relates to a wrapping machine particularly adapted for wrapping packages of either round or square shape, readily interchangeable wrapping heads being provided for the round or square packages as desired.

One object of the invention is to provide a relatively simple arrangement for quickly adapting the machine for round or square packages by means of removable rotary wrapping heads supported entirely from one side and including openable pockets of different character in the two wrapping heads, but operable in a similar manner by the same mechanism of the machine and particularly certain cams thereof so that no change in the cams is necessary when changing from round to square wrapping operations or vice versa.

Another object is to provide a wrapping head of barrel-like character open at one end and supported for rotation at its other end only so that hold-down and package push-out instrumentalities can operate inside the barrel and can be supported at its open end so as to project thereinto with the operating mechanism therefor entirely outside of the barrel.

Still another object is to provide a wrapping head having pockets wherein a wrapper is wrapped around a stack of articles such as cookies or sandwiches, the pockets being openable to receive the articles and wrapper, closable to carry the same during the wrapping operation and openable again for discharge of the wrapped articles therefrom.

A further object is to provide wrapping instrumentalities for the various flaps of the wrapper to wrap them around the package, and a plurality of heaters for heating the flaps and thereby adhering them to the main body of the package.

Still a further object is to provide a cam arrangement for opening and closing the pockets of the wrapping head and for moving the heaters mentioned in the above object into and out of contact with the packages during the wrapping thereof, the cam arrangement being oscillatable so as to open and close the pockets and to move the heaters into and out of contact during a stationary part of the intermittent cycle of rotation of the wrapping head, the head being rotated by a Geneva movement and the oscillations of the cam being timed in relation thereto so as to be active only when the head is inactive because of the dwell of the Geneva movement.

An additional object is to provide heaters that are adaptable for either round or square packages and which can be quickly adjusted for one or the other merely by rotatably reversing them so that either a curved face or a flat face thereof contacts the packages, depending on whether round or square packages, respectively, are being wrapped.

With these and other objects in view, our invention consists in the construction, arrangement and combination of the various parts of our wrapping machine, whereby the objects above contemplated are attained, as hereinafter more fully set forth, pointed out in our claims and illus-

2

trated in detail on the accompanying drawings, wherein:

Fig. 1 is a plan view of part of a wrapping machine including the mechanism which constitutes our invention and shows the relationship of various parts thereof.

5 Fig. 2 is an enlarged side elevation of Fig. 1, portions of Fig. 1 being shown in section on the line 1—1 of Fig. 2.

Fig. 3 is a front elevation of Fig. 2, looking in the direction of the arrow 3 adjacent the left side thereof.

Fig. 4 is a vertical sectional view of the line 4—4 of Fig. 3 showing one of the cam actions of our machine.

Fig. 5 is a vertical sectional view on the line 5—5 of Fig. 3 showing another cam action thereof.

Fig. 6 is a vertical sectional view on the line 6—6 of Fig. 3.

Fig. 7 is a vertical sectional view on the line 7—7 of Fig. 6.

Fig. 8 is a vertical sectional view on the line 8—8 of Fig. 7.

Fig. 9 is a right side elevation of a take-out conveyor and a portion of a take-away conveyor together with adjacent portions of our wrapping machine.

Fig. 10 is a partial side elevation and partial sectional view of the lower portion of the wrapping head for square articles taken from the reverse side in relation to Fig. 6 to show how the parts of the pocket are adapted for square articles instead of round articles, as are the pockets of Fig. 8.

Fig. 11 is a perspective view of a stack of round articles showing the association of a wrapper therewith as the articles are elevated from the position shown in Fig. 8 into a pocket of the wrapping head.

Fig. 12 is a similar perspective view showing the way the wrapper is folded to make the first end flaps as the articles are introduced fully into the pocket of the wrapping head.

Fig. 13 is a diagrammatic view showing the circumferential flap of the wrapper being folded by a folder blade.

Fig. 14 is a similar diagrammatic view showing the second circumferential flap being folded.

Fig. 15 is a further diagrammatic view showing the second end flap being folded as the partially wrapped article is pushed into the take-out conveyor of Fig. 9.

Fig. 16, on the sheet of drawings with Fig. 2, shows the third end flap being folded by one of the folder elements shown in Fig. 9; and

Fig. 17 is a similar diagram adjacent Fig. 7 showing the final or fourth end fold being formed by a folder element of Fig. 9.

50 On the accompanying drawings we have used the reference numeral 22 to indicate a vertical frame and 28 a table supported at the top of the vertical frame.

Fig. 2 shows the right side of the machine when considering the intake end as the rear end of the machine. The rear end is at the right in Fig. 8 and an intake conveyor 30 is there shown, while at the left side of Fig. 9 a take-away conveyor 32 is shown extending toward the front of the machine.

60 Referring to Figs. 2 and 7, a Geneva housing 34 is suitably supported on the upright frame 12 and the table 28 and a Geneva housing cover 36 is secured thereto to form an enclosure for a Geneva movement. A head shaft 38 is journaled in bearings 40 and 42, carried by the housing 34 and its cover 36, and supported on the righthand end thereof is a "round head" indicated generally as RH. This is a handling head for round articles, such as disc-like cookies or sandwiches, whereas we also provide a "square head" SH (see Fig. 10) interchangeable with the round head and provided for wrapping square articles such as square cookies, crackers, or sandwiches.

70 The Geneva movement above referred to consists of

a Geneva disc 44 secured to the shaft 38 and a Geneva rotator 46 carrying a roller 47 to enter the slots of the Geneva disc. The rotator 46 is secured to a Geneva rotator shaft 48. The shaft 48 is also journaled in the housing 34 and its cover 36, as shown in Fig. 7.

The shaft 48 is driven by a sprocket 50 (Figs. 3 and 7) connected by a chain 52 (Fig. 3) to suitable power means for driving the chain, usually an electric motor and variable speed reducing mechanism.

Referring to Fig. 3, a gear housing 66 is shown with a cam shaft 68 extending therethrough. We are not concerned with the mechanism in the housing 66, but only with the cam shaft 68 for driving certain mechanisms of our present invention. The cam shaft 68 has a sprocket 70 thereon, driven by a chain 72 from the power mechanism above referred to and a chain 74 is driven by a sprocket 80 on the Geneva rotator shaft 48.

Referring to Fig. 9, a take-out conveyor chain 84 is shown carrying take-out elements 86 of angle shape. The chain 84 extends around sprockets 88 and 90 for conveying the wrapped packages from the round head RH to the take-away conveyor 32. The sprocket 88 is secured to a shaft 88a. The take-out conveyor chain 84 is driven in an intermittent manner by means of a chain 102 on a sprocket 104 (see Fig. 3) secured to the head shaft 38. The chain drives a sprocket (not shown) on the shaft 88a.

The chain 84 and its elements 86 deliver the wrapped packages to a plate 92 (Fig. 9) spanning the distance between the sprocket 90 and the conveyor 32, and sweep fingers 96 are provided to move the packages along this plate. The sweep fingers are driven by a package hold-down belt supported 94 on a frame 98 which is pivoted on a shaft 95 for the sweep fingers so that the frame can be raised in the event trouble is experienced in the proper wrapping of any package. The frame 98 is shown in the lowered or operative position with a shaft 95a thereof resting on a post 95b. A shaft 32a of the conveyor 32 and the shaft 95 are driven from the shaft 76 by suitable means not illustrated.

Referring now to the details of the round head RH (see particularly Figs. 6, 7 and 8 respectively) the round head RH is barrel-like in character, having a disc 106 as one end, a ring 108 as the other end, and the two connected together by a plurality of connector struts 110. The disc 106 is removably secured by bolts 112 to a flange 114 mounted on the head shaft 38.

As shown in Fig. 8, 8 pockets are provided in the round head RH, and a stationary pocket end 116 is illustrated on a mounting rod 118. Referring to Fig. 7, the rod 118 is rigidly mounted in and carried by the ring 108. The other end 120 of the pocket is provided in the form of a movable member, carried by a slide rod 122 which is urged to the position shown by a spring 126 that permits slight movement of the end 120 away from the end 116 when the cookies enter between them.

Returning to Fig. 8, a stationary pocket side 128 is supported on a crossbar 110, and a movable side 130 is supported by an arm 132 mounted on a rock shaft 134, one for each of the eight pockets. Thus, the elements 116, 120, 128 and 130 form an openable pocket, the open position being shown for the pockets at stations (1), (7) and (8), the pockets of the head being designated (1) to (8) in Figs. 6 and 13. Each of the rock shafts 134 has a rock arm 136 mounted thereon and terminating in a roller 138. The rollers 138 are engaged with a cam 142 having a lobe 144 by means of springs 140.

The cam 142 as shown in Fig. 12 is oscillatable on a hub 146 of the Geneva housing 34, and oscillations are imparted to it by a link 150 connected at one end to a ball head 148 secured to the cam 142, and at its other end to a bell crank 152. The bell crank 152 is oscillatable on a stud 154, carried by a bracket 156, which is secured to the vertical frame 22 (see Figs. 2 and 3). The lower end

of the bell crank 152 carries a roller 158 cooperating with a barrel cam 160, the cam groove of which is indicated at 162. The cam 160 is secured to the cam shaft 68, and thereby rotatable in unison therewith and in timed relation to the wrapping machine.

Referring to Figs. 3, 6, 7 and 8, three heaters H¹, H² and H³ are provided which may be of the electrically energized type. Three brackets 164 are secured to the Geneva housing 34, and project toward the right side of the machine. The outer end of each bracket carries a bearing 167 in which a rock shaft 166 is journaled. A heater carrying arm 168 is secured to each rock shaft for supporting the heaters H¹, H² and H³. A rock arm 170 is also secured to each rock shaft and terminates in a roller 172 for coaction with a cam 174. The cam has three lobes L¹, L² and L³ for the rollers 172 of the respective heaters H¹, H² and H³. The cam 174 is secured to the cam 142 and accordingly oscillates therewith under control of the cam 160 on the cam shaft 68. Details of operation will be explained hereinafter. Each heater has a flat face 176 and opposite thereto a curved face 178 and these faces are preferably serrated as shown in Fig. 7. One of the heating elements for the heaters is shown at HE in Fig. 8, being of the metal-sheathed type received in a bore of the heater.

The intake conveyor 30 is provided with pockets 180 to receive articles to be wrapped such as cookies or sandwiches 182 (see Fig. 8). These are the round type. A ram 184 having a head 186 is adapted to pass upwardly through the bottom of the pocket 180 to raise the articles 182 through an opening 188 of the table 28 against a sheet of wrapping paper 190, and to move the articles and the paper into the pocket of the head RH at station (1). The ram 184 shown in Figs. 2 and 8 is reciprocated vertically in timed relation to the operating cycles of the machine but the mechanism to accomplish such reciprocation is not described in detail as the details thereof will be found in the prior patents of Sandberg, Nos. 2,567,405, 2,603,048 and 2,642,707 of our assignee.

Wrapping paper may be supplied from a reel and may be cut by a paper cutting mechanism as disclosed in Sandberg patents into individual wrappers 190 shown in Figs. 5, 6, 7 and 8 under the control of the electric eye mechanism shown in said patents. The mechanism just referred to is not part of our present invention and therefore will not be described in greater detail.

Referring to Fig. 11, the coaction of the wrapper 190 with the stack of articles 182 is illustrated in the relative positions they assume just after the articles have passed through the opening 188 of the table 28. When the article and wrapper are completely in the pocket of the head RH at station (1) the first end flaps will have been folded by the pocket ends 116 and 120 as illustrated in Fig. 12 and this flap is numbered 1. The next operation is illustrated in Fig. 13 where the first circumferential flap 1A is being folded by a folder blade 198. The blade 198 is carried by a slide 200 slidable in a slideway 202 mounted on the table 28 (see Figs. 2 and 8). A link 204 has one end (Figs. 2, 3 and 5) pivoted to the slide 200 and its other end pivoted to the upper end of a lever 206. The lever 206 is oscillatable on a stud 208 carried by a bracket arm 210 extending from the bracket 156. The lower end of the lever 206 carries a roller 212 (Fig. 15) coacting with a barrel cam 214, the cam groove being shown at 216.

After the stack of articles 182 and the wrapper 190 are completely in the pocket at station (1) the movable side 130 thereof closes by clockwise rotation of the cam 142 in Fig. 6 so that its lobe 144 leaves the roller 138 of the pocket side 130 at station (1) and simultaneously the lobes L¹, L² and L³ of the cam 174 are rocked clockwise into engagement with the rollers 172 of the three heaters so that they are raised from the position shown in contact with the articles at stations (3), (4) and (5) and the head RH is then ready to rotate.

As the head RH rotates, the second circumferential flap of the package indicated at 1B in Fig. 14 is folded around the articles by a curved plate 218 which is stationarily mounted. Thereupon the partially wrapped package at station (2), having both circumferential flaps and the first end folds (1) completed, is ready to move to stations (3), (4) and (5) where heat is applied as the heaters are moved into contact with the flap 1B at these stations.

The package is then ready to move past an idle station (6) to station (7) where it is to be ejected into position for engagement by the take-out elements 86 of the take-out conveyor chain 84. This is accomplished by a push-out rod having a push-out head 222 thereon, the rod being L-shaped as shown in Fig. 1 and secured to a rack 224 which is slidable in a rack and sector housing 226. Within the housing 226 a gear sector 227 meshes with the rack 224 and is mounted on a rock shaft 228 journaled in the housing 226.

Within the rack and sector housing 226 is a gear sector 227 in mesh with the rack 224 and mounted on a rock shaft 228 journaled in the housing. Exteriorly of the housing an arm 230 extends from the rock shaft and a link 232 depends therefrom and terminates in a closed fork 234 straddling the cam shaft 68. The fork carries a roller 236 coating with a barrel cam 238 on the cam shaft, the cam having a groove 240 therein for the roller. Accordingly the cam vertically reciprocates the link 232 for oscillating the gear sector 227 and thereby reciprocating the rack 226 and the push-out head 222. This head is shown in the pushed out position in Fig. 13, after having extended through the pocket at station (7) of the head RH, and the retracted position of the head 222 is shown by dotted lines, within the ring 108 so as not to interfere with the intermittent rotation of the head RH. The cam 238 is set, of course, so as to properly time the reciprocations of the push-out head 222 to occur at a time the head RH is stationary.

Referring to Figs. 1, 3, 7 and 8, a paper hold-down shoe 242 is illustrated. This shoe is loosely pivoted on the lower end of a rod 244, telescopically mounted in a tube 250, and normally biased downwardly relative thereto by a spring 246 in the tube. The tube 250 is vertically slidable in a bracket 248 extending upwardly from the table 28 and having a foot 249 secured thereto (as shown in Fig. 1) and into the head RH. A lateral pin 252 is carried by the upper end of the tube 250, and the upper end of a link is pivoted thereon, its lower end being pivoted to an arm 256. The arm 256 is mounted on a rock shaft 258 journaled in the bracket 248.

A second arm 260 is secured to the rock shaft and a link 262 has one end thereof pivoted to the upper end of this arm. The other end of the link is pivoted to a boss 264 (see Fig. 2) secured to the rack 224 so as to be movable therewith. Accordingly when the push-out head 222 is farthest to the left in Fig. 8 the hold-down shoe 242 is farthest down in its travel and ready to be engaged by the paper 190 as the paper is raised by the articles 182 engaging therewith. Thereafter as the articles and wrapper are moved into the pocket at station (1) of the head RH the tube 250 is retracted but not quite as fast as the articles enter the pocket of the head RH, and therefore the spring 246 is under predetermined tension to hold the shoe 242 against the wrapper 190 to prevent it from slipping in any lateral direction relative to the articles being wrapped. Finally when the shoe 242 is in its raised position it is clear of the pocket so as to permit the intermittent rotation of the head RH without interference.

Referring to Figs. 1 and 9 folder elements 266 are illustrated which form the second end fold on the package as illustrated in Fig. 15. This second end fold is labeled 2.

After the second end fold is formed, one of the take-out elements 86 engages the partially wrapped package to carry it to the plate 92. Further folder elements 268

and 270 are shown, these being the usual "plow" or twisted blade type, and these are operable for forming the third and fourth end flaps 3 and 4 as in Figs. 16 and 17. Thereafter the package passes between heater shoes 272 (Fig. 9) to seal the end flaps 1, 2, 3 and 4 and the kick-out fingers 96 move the completed package across the plate 92 onto the take-away conveyor 32.

In Fig. 10, SH indicates a head for wrapping square articles, the pocket being illustrated at station (1). In 10 place of the stationary pocket sides 128 and 130, pocket sides 128a and 130a of somewhat different shape are used for the square articles which are indicated at 182a. A disc 106a and a ring 108a are provided to form the framework of the head similar to the head RH, but the two 15 are connected by struts 110a adjacent the periphery of the ring 108a rather than adjacent its inner diameter as are the struts 110 in the round head (Fig. 8).

In addition to the rock shaft 134a, a second one, 134b is used for the pocket side 128b. The two are operatively connected together for simultaneous movement by 20 means of a first gear sector 174 and a second gear sector 176 meshed together as illustrated. The rock shaft 134a (the same as the rock shaft 134) carries an arm 136a and a roller 138a as shown in dotted lines for coaction 25 with the lobe 144 of the cam 142. Other comparable parts, such as the springs 140a, are also used. Also, additional springs 178 back up the pocket sides 128a and 130a, tending to close them.

When it is desirable to change from wrapping round 30 articles to wrapping square articles, it is merely necessary to remove the round head RH by removal of the screws 112 shown in Fig. 7 and substitute the square head SH. The heaters H¹, H² and H³ are turned over so that their flat sides 176 rather than their curved sides 178 35 are toward the head. Thereafter, when the machine is put into operation the cam 142 will coat with the rollers 138a in the same manner that they coated with the rollers 138 and the square articles will be properly wrapped in the machine.

40 From the foregoing specification it will be obvious that we have provided a wrapping machine wherein round or square articles can be wrapped with a minimum of changes required to adapt the machine for either type of article. Contrasted with the Sandberg Patent No. 2,642, 45 707, only one of the end folds is formed in the head rather than all four. Both circumferential flaps are formed in substantially the same manner as in the Sandberg patent and our arrangement permits more effective heating of the circumferential flaps by the heaters H¹, H² and H³ prior to finishing the wrapping of the ends of the package. The second, third and fourth end flaps are wrapped and sealed after the package leaves the head. This arrangement permits the construction of a head that is considerably less expensive to manufacture than the one 50 shown in the Sandberg patent and permits the folding of the second, third and fourth end flaps and the heating thereof in the take-out conveyor shown in Fig. 7 where the frame 98 is readily movable to the raised position shown in Fig. 3 to clear out any miswrapped packages.

55 Some changes may be made in the construction and arrangement of the parts of our wrapping machine without departing from the real spirit and purpose of our invention, and it is our intention to cover by our claims any modified forms of structure or use of mechanical equivalents which may reasonably be included within their 60 scope.

We claim as our invention:

1. In a wrapping machine of the character disclosed, a wrapping head of barrel-like character supported for 70 rotation at one end and having its center opening to the opposite end of the head, said head having circumferentially spaced pockets to receive articles and wrappers therefor, each of said pockets having a pair of ends and a pair of sides, at least one of said sides being openable to receive an article and a wrapper therefor, means for

moving the article and wrapper into the pocket at a first station of said head, said pocket ends folding the first end flaps of the wrapper, cam means for opening said openable pocket side as the article and wrapper enter the pocket, a folder blade movable to fold a first circumferential flap of the wrapper, means for intermittently rotating said head a pocket at a time, a second blade engageable with the second circumferential flap of the wrapper to fold it around the article overlapping the first circumferential flap as the pocket is advanced to a second station during rotation of the head, a plurality of heater shoes at further stations of said head, a second cam means for engaging said heater shoes with the package while the head is stationary and disengaging them from the package while the head is rotating, push-out means entering said head through its open end to push the partly wrapped article out of the head by radially outward movement relative thereto at a still further station, said cam means also opening the pocket at said last station, end flap folder blades for folding the second end flaps of the wrapper as the package is so pushed, take-out conveyor means for moving the article thereafter, third and fourth end flap folder blades for folding the third and fourth end flaps of the wrapper as the package is further advanced by said take-out conveyor means, and heaters beyond said third and fourth end flap folder blades for heating the end folds of the wrapper, said first and second cam means, said folder blade, said means for intermittently rotating said head, said push-out means and said take-out conveyor means being cyclically operated in accordance with the cycles of operation of said wrapping machine.

2. In a wrapping machine, a wrapping head of barrel-like character supported for rotation at one end and having its center opening to the opposite end of the head, said head having circumferentially spaced pockets to receive articles and wrappers therefor, each of said pockets having a pair of ends and a pair of sides, one of said sides being openable to receive an article and a wrapper therefor, means for moving the article and wrapper into the pocket at a first station of said head, said pocket ends folding the first end flaps of the wrapper, cam means for opening said openable pocket side as the article and wrapper enter the pocket, a folder blade movable to fold a first circumferential flap of the wrapper, means for intermittently rotating said head a pocket at a time, a stationary blade engageable with a second circumferential flap of the wrapper to fold it around the article overlapping the first circumferential flap as the pocket is advanced to a second station during rotation of the head, push-out means entering said head through its open end and movable radially outward thereof to push the partly wrapped article out of the head at a further station thereof, end flap folder blades for folding the second end flaps of the wrapper as the package is so pushed, take-out conveyor means for moving the article thereafter, third and fourth end flap folder blades for folding the third and fourth end flaps of the wrapper as the package is further advanced by said take-out conveyor means, said cam means, said folder blade, said means for intermittently rotating said head, said push-out means and said take-out conveyor means being cyclically operated in accordance with the cycles of operation of said wrapping machine.

3. A wrapping machine comprising a wrapping head of barrel-like character removably supported for rotation at one end and having its center opening to the opposite end of the head, said head having circumferentially spaced pockets to receive articles and wrappers therefor, each of said pockets having a pair of ends and a pair of sides, said sides being openable to receive an article and a wrapper therefor, means for moving the article and wrapper into the pocket at a first station of said head, wrapper hold-down means entering said head through its open end and movable through a pocket thereof at said first station for holding the wrapper against the article, said pocket ends

5 folding the first end flaps of the wrapper, a first means for opening said pocket sides as the article and wrapper enter the pocket, a folder blade movable to fold a first circumferential flap of the wrapper, means for intermittently rotating said head a pocket at a time, a second blade curved to engage a second circumferential flap of the wrapper to fold it around the article overlapping the first circumferential flap as the pocket is advanced to a second station during rotation of the head, push-out means entering said head through its open end to push the partly wrapped article out of the head at a still further station of said head, and folder blades for folding the remaining end flaps of the wrapper after the package leaves said first means, said folder blade and said means for intermittently rotating said head being cyclically operated.

4. In a wrapping machine, a wrapping head supported for rotation and having circumferentially spaced pockets to receive articles and wrappers therefor, each of said pockets having a pair of ends and a pair of sides, at least one of said sides being openable to receive an article, means for moving the article and wrapper into the pocket at a first station of said head, said pocket ends folding the first end flaps of the wrapper, cam means rotatable about the axis of rotation of said wrapping head for opening said openable sides as the article and wrapper enter the pocket and while said head is stationary, a folder blade movable to fold a first circumferential flap of the wrapper also while said head is stationary, means for intermittently rotating said head, a stationary blade engageable with a second circumferential flap of the wrapper to fold it around the article overlapping the first circumferential flap during rotation of said head, push-out means to push the partly wrapped article out of the head at a still further station thereof, end flap folder blades for folding the second end flaps of the wrapper as the package is so pushed, means for thereafter folding the third and fourth end flaps of the wrapper, said cam means, said folder blade, said means for intermittently rotating said head and said push-out means being cyclically operated.

5. In a wrapping machine, a wrapping head supported for rotation and having circumferentially spaced pockets to receive articles and wrappers therefor, each of said pockets having a pair of ends and a pair of sides, at least one of said sides being openable to receive an article, means for moving the article and wrapper into the pocket at a first station of said head, wrapper hold-down means located within said head and movable through a pocket thereof at said first station for holding the wrapper against the article, said pocket ends folding the first end flaps of the wrapper, cam means for opening said openable pocket side as the article and wrapper enter the pocket, a folder blade movable to fold a first circumferential flap of the wrapper, means for intermittently rotating said head a pocket at a time, a stationary blade engageable with a second circumferential flap of the wrapper to fold it around the article overlapping the first circumferential flap as the pocket is advanced to a second station during rotation of said head, push-out means to push the partly wrapped article out of said head at a still further station thereof, folder blades for folding the second end flaps of the wrapper as the package is so pushed, take-out conveyor means for moving the article thereafter, third and fourth folder blades for folding the third and fourth end flaps of the wrapper as the package is further advanced by said take-out conveyor means, said cam means, said wrapper hold-down means, said folder blade, said means for intermittently rotating said head, said push-out means and said take-out conveyor means being cyclically operated in accordance with the cycles of operation of said wrapping machine.

6. A wrapping machine comprising a wrapping head having one end supported for rotation and its opposite end open, said head having circumferentially spaced pockets to receive articles and wrappers therefor, each of said pockets having a pair of ends and a pair of sides,

said sides being openable to receive an article and a wrapper therefor, means for moving the article and wrapper into the pocket at a first station of said head while the pocket at said station is open, wrapper hold-down means located within said head and movable through said pocket at said first station for holding the wrapper against the article as the article and wrapper enter said pocket, said pocket ends folding the first end flaps of the wrapper, cam means for opening said openable sides as the article and wrapper enter the pocket, a folder blade movable to fold a first circumferential flap of the wrapper, means for thereafter rotating said head, a stationary blade engageable with a second circumferential flap of the wrapper to fold it around the article as the article and wrapper enter said pocket, said pocket ends folding the first end flaps of the wrapper, cam means for opening said openable sides as the article and wrapper enter the pocket, a folder blade movable to fold a first circumferential flap of the wrapper, means for thereafter rotating said head, a stationary blade engageable with a second circumferential flap of the wrapper to fold it around the article overlapping the first circumferential flap as said head is rotated, a plurality of heater shoes at further stations of said head, a second cam means for engaging said heater shoes with the package while the head is stationary and disengaging them from the package while the head is rotating, push-out means entering said head through its open end to push the partly wrapped article out of the head at a still further station thereof, said cam means also opening the pocket at said still further station, folder blades for folding the second end flaps of the wrapper as the package is so pushed, third and fourth end flap folder means for the partially wrapped package, and heaters for heating the end folds of the wrapper, said first and second cam means, said folder blade, said means for rotating said head, said push-out means being cyclically operated in accordance with the cycles of operation of said wrapping machine, said wrapper hold-down means being operated simultaneously with said push-out means.

7. In a wrapping machine of the character disclosed, a wrapping head having one end supported for rotation and having its opposite end open, circumferentially spaced pockets in said head to receive articles and wrappers, each of said pockets having a pair of ends and a pair of sides, at least one of said sides being openable to receive an article and a wrapper therefor, means for moving the article and wrapper into the pocket at a first station of said head, wrapper hold-down means extending within said head through its open end and movable through the pocket at said first station for holding the wrapper against the article as said pocket ends fold the first end flaps of the wrapper, cam means for opening said openable side as the article and wrapper enter the pocket, folder blades to fold first and second circumferential flaps of the wrapper, a plurality of heater shoes at further stations of said head, a second cam means for engaging said heater shoes with the package while the head is stationary and disengaging them from the package while the head is rotating, push-out means entering said head through its open end to push the partly wrapped article out of the head at a still further station thereof, blades for folding the second end flaps of the wrapper as the package is so pushed, means for thereafter folding third and fourth end flaps of the wrapper and heaters beyond said last means for heating the end folds of the wrapper, said wrapper hold-down means, said first and second cam means, said folder blade, said means for intermittently rotating said head and said push-out means being cyclically operated.

8. In a wrapping machine of the character disclosed, a wrapping head having circumferentially spaced pockets to receive articles and wrappers therefor, each of said pockets having a pair of ends and a pair of sides, at least one of said sides being openable to receive an article and a wrapper therefor, means for moving the article and wrapper into the pocket at a first station of said head, wrapper hold-down means located within said head and movable through a pocket thereof at said first station for holding the wrapper against the article, said pocket ends folding the first end flaps of the wrapper, cam means for opening said openable side as the article and wrapper enter the pocket, a folder blade movable

to fold a first circumferential flap of the wrapper, means for intermittently rotating said head a pocket at a time, a stationary blade engageable with a second circumferential flap of the wrapper to fold it around the article as the pocket is advanced to a second station during rotation of the head, a plurality of heater shoes at further stations of said head, said shoes having curved and flat faces and being reversible to present either face to the articles in said pockets, a second cam means for engaging said heater shoes with the package while the head is stationary and disengaging them from the package while the head is rotating, means to push the partly wrapped article out of the head at a still further station thereof, folder blades for folding the second end flaps of the wrapper as the package is so pushed, take-out conveyor means for moving the article thereafter, third and fourth folder blades for folding the third and fourth end flaps of the wrapper as the package is further advanced by said take-out conveyor means, said wrapper hold-down means, said first and second cam means, said folder blade, said means for intermittently rotating said head, said push-out means and said take-out conveyor means being cyclically operated in accordance with the cycles of operation of said wrapping machine.

9. In a wrapping machine of the character disclosed, a wrapping head comprising a disc supported for rotation, a ring connected therewith in spaced relation thereto, circumferentially spaced pockets between said disc and said ring to receive articles and wrappers therefor, each of said pockets having a pair of ends and a pair of sides, at least one of said sides having a terminal end to retain an article in the pocket and being openable to receive the article and a wrapper therefor, means for moving the article and wrapper into the pocket at a first station of said head while said pocket side is open, said pocket ends folding the first end flaps of the wrapper, cam means for opening said openable side as the article and wrapper enter the pocket and for thereafter closing it to retain the article, means to fold a first circumferential flap of the wrapper, means for intermittently rotating said head one pocket at a time, means to fold a second circumferential flap of the wrapper around the article overlapping the first circumferential flap as the pocket is advanced to a second station during rotation of said head, push-out means entering said head through said ring and movable radially through a pocket of said head to push the partly wrapped article out of the head at a still further station thereof, and folder blades for thereafter folding the second, third and fourth end flaps of the wrapper.

10. A wrapping machine comprising a wrapping head comprising a disc supported for rotation, a ring spaced therefrom, cross members connecting said ring to said disc, circumferentially spaced pockets between said disc and ring to receive articles, each of said pockets being openable to receive an article and a wrapper therefor and having an inturned flange to hold the article and wrapper in the pocket, means for moving the article and wrapper into the pocket at a first station of said head, cam means for opening the pocket as the article and wrapper enter the pocket, a folder blade movable to fold a first circumferential flap of the wrapper, means for intermittently rotating said head a pocket at a time, a stationary blade engaged with the second circumferential flap of the wrapper to fold it around the article overlapping the first circumferential flap as the pocket is advanced to a second station during rotation of said head, push-out means entering said head through its open end to push the partly wrapped article out of the head at a further station thereof, said cam also opening the pocket at said further station, folder blades for folding the second end flaps of the wrapper as the package is so pushed, take-out conveyor for moving the articles thereafter, third and fourth folder blades for folding the third and fourth end flaps of the wrapper as it is moved by said take-out conveyor, said

cam means, said folder blades, said means for intermittently rotating said head, said push-out means and said take-out conveyor being operated cyclically in accordance with the cycles of operation of the wrapping machine.

11. A wrapping machine comprising a wrapping head comprising a disc supported for rotation, a ring spaced therefrom, cross members connecting said ring to said disc, circumferentially spaced pockets between said disc and ring to receive articles and wrappers therefor, each of said pockets having a pair of ends and a pair of sides which are openable to receive an article and a wrapper therefor and having an inturned flange to hold the article and wrapper in the pocket, means for moving the article and wrapper into the pocket at a first station of said head, said ends folding the first end flap of the wrapper, cam means for opening said openable sides as the article and wrapper enter the pocket, a folder blade movable to fold a first circumferential flap of the wrapper, means for intermittently rotating said head a pocket at a time, a stationary blade engaged with the second circumferential flap of the wrapper to fold it around the article overlapping the first circumferential flap as the pocket is advanced to a second station during rotation of the head, push-out means entering said head through said ring and having means located in the space between said disc and said ring, said means being movable through said pockets to push the partly wrapped article out of the head at a still further station, said cam means opening the openable sides of the pocket as said push-out means pushes an article out of said head, folder blades for folding the second end flaps of the wrapper as the package is so pushed, means for moving the articles thereafter, means for folding the third and fourth end flaps of the wrapper as it is moved by said last means, said cam means, said folder blades, said means for intermittently rotating said head, said push-out means and said last means being operated in accordance with the cycles of operation of the wrapping machine.

12. A wrapping machine comprising a wrapping head comprising a disc supported for rotation, a ring spaced

5 10 15 20 25 30 35 40

therefrom, cross members connecting said ring to said disc, circumferentially spaced pockets between said disc and ring to receive articles and wrappers therefor, each of said pockets having a pair of ends and a pair of sides and being openable to receive an article and a wrapper therefor, at least one of said sides having an inturned flange to hold the article and wrapper in the pocket, means for moving the article and wrapper into the pocket at a first station of said head, said ends folding the first end flap of the wrapper, wrapper hold-down means located in the space between said disc and said ring and movable through a pocket of said head at said first station for holding the wrapper against the article, cam means for opening the pocket at said first station as the article and wrapper enter the pocket, means to fold first and second circumferential flaps of the wrapper, means for intermittently rotating said head one pocket at a time, push-out means entering said head through said ring and having means located in the space between said disc and said ring, said means being movable through said pockets to push the partly wrapped article out of the head at a last station thereof, folder blades for folding the second end flaps of the wrapper as the package is so pushed, said cam means opening the pocket at said last station, take-out conveyor means for moving the articles thereafter, and third and fourth end flap folder blades for folding the third and fourth end flaps of the wrapper as it is moved by said take-out conveyor means.
